UNITED STATES PATENT OFFICE

163,296

KEY HOLDER

Tony Lama, El Paso, Tex.

Application February 15, 1949, Serial No. 870

Term of patent 14 years

(Cl. D87—3)

To all whom it may concern:

Be it known that I, Tony Lama, a citizen of the United States, residing at El Paso, in the county of El Paso and State of Texas, have invented a new, original, and ornamental Design for a Key Holder, of which the following is a specification, reference being had to the accompanying drawings, forming a part thereof.

Figure 1 is a back elevational view of a key holder, showing my new design;

Figure 2 is a view of one edge;

Figure 3 is a view of the other edge; and

Figure 4 is a plan view of the key holder opened to a flat condition.

I claim:

The ornamental design for a key holder, as shown.

TONY LAMA.
